ENERGY RECLAMATION MEANS

Frazer W. Gay, Metuchen, N. J.

Application March 7, 1944, Serial No. 525,427

6 Claims. (Cl. 122—40)

This invention relates to a heat reclamation system useful in recovering the heat normally wasted in flue gases, and especially as a means for reclaiming heat in the exhaust gases of an engine using steam, and employing highly compressed air in combustion with fuel to highly superheat said steam.

In the present invention, water is heated by direct contact with the waste heat gases in the low temperature range (up to about 200° F.). In this range, the water is brought into intimate contact with the waste gases (as by spraying). The partly heated water is then carried confined in pipes to a relatively great depth and these pipes are continually bathed by the waste gases flowing in counterflow relation thereto, so that as the water descends, the pressure of the water in the pipes by reasons of depth increases faster than its vapor pressure by reason of temperature, and free steam is not formed. After the water has been carried down to the maximum depth and at the same time brought up to the desired maximum temperature, it is brought back to the surface of the ground through a plurality of evaporating chambers. The steam that flashes off in each said evaporating chamber is then passed to and through a power steam turbine on its way to a condenser.

It is an object of the present invention to construct a boiler deriving its heat from the combustion of air and fuel and having a heat absorbing portion and a separate steam evaporating portion respectively arranged to heat the water as it descends into regions of greater hydrostatic pressure and to collect the evaporating steam as the water returns to its normal level.

It is an object of the present invention to construct a steam generating unit having a natural flow of water through sealed container means from a hot source to a cold source, in which the steam pressure is balanced by the hydrostatic pressure of the water, and the water is allowed to flow freely from said hot source to said cold source without being required to pass through high pressure restraining valves, and in which any restraining means installed operates only to prevent a reverse flow or to retard a too rapid positive flow.

It is an object of the present invention to cause water to flow in counter-flow direction to a heat energy containing fluid from which it is desired to extract heat as it falls in temperature, and to arrange that the water flows first through heat absorbing means and then through evaporators so as to make this heat available at

small step in temperature, whereby the energy of the steam is utilized from a top temperature always close to the temperature at which said energy was extracted from said above mentioned heat energy containing fluid.

It is a further object of this invention to pass an energy transfer fluid in counter-flow relation to heat energy containing fluids; to provide energy utilization equipment adapted to change heat energy taken from said energy transfer fluid into mechanical power, and to increase the stream of energy transfer fluid through those temperature ranges of said energy containing fluid able to provide an increased energy flow.

It is a further object of the present invention to use water as an energy transfer medium between a hot gas and an engine, and to provide recirculating means through which the water can flow from approximately atmospheric pressure to a great depth, and then upward to a height above normal atmospheric level, i. e., into a vacuum range, and to provide means for allowing the gas to heat the water as the water flows to said great depth, and to provide short risers in which the rising water cools by evaporation, and the vapors released cause the water to circulate, since the rising and cooling column of mixed water and steam is lighter than the falling and heating column, whereby a great quantity of water is circulated through the water heating boiler and the evaporators with a minimum of motor forcing, and whereby, in some cases, a restraining force must be used to maintain the desired rate of water flow so as to deliver a maximum amount of water at the desired high temperature.

The invention is clearly illustrated in the accompanying drawings, in which:

Fig. 1 is a schematic elevational view of a power house partially broken away to show the turbine room interior.

Fig. 2 is a ground floor plan of the central portion of the heat reclamation room 45 of Fig. 1, and is taken along the line 2—2 of Fig. 3.

Fig. 3 is a cross sectional view of the central portion of the heat reclamation room 45 of Fig. 1, and is taken along the line 3—3 of Fig. 2.

Fig. 4 is a fragmentary sectional view taken along the line 4—4 of Fig. 2.

Fig. 5 is a schematic plan view of the turbine room and condenser floor of the heat reclamation room 45 of Fig. 1.

Similar reference numbers refer to similar parts.

In Fig. 1 the reference character 1 indicates a

boiler room wall, the roof of which is shown broken away. The boiler comprises a lower drum 7 connecting to a back distributing section 10 and a front distributing section 9. Water tubes 8, 8, 8, etc. connect sections 9 and 10. The drum 7 is mounted on the rear furnace wall 17 and section 9 is mounted on the front furnace wall 18. The furnace is equipped with firing door 4, ash door 5 and grate bars 3. The mixture of steam and water is carried to the upper drum 6 where the steam is separated out, leaving the water level at 13. Water is carried back to the rear distributing section by the tubes 12. A superheater means draws steam from the dome 14 through the hot furnace or flue gases by pipe 16. Walls 26, 26 are restricted at the top of the boiler to the flue gas passage 51, carrying these flue gases to heat reclaiming building 45.

An air compressor 19, driven by motor 20, supplies compressed air to combustion chamber 21 wherein oil and other fuel is burned to further superheat the steam supplied by pipe 16. The highly heated gases pass through turbine 22 to the exhaust conduit 15, and thence to heat reclaiming building 45. Turbine 22 drives electric generator 23 which supplies part of its power to motor 20.

No claim is made to novelty in the above arrangement, and for further description of a power house, similar to the one described above, reference is made to U. S. Patent No. 872,806 issued to S. Z. De Ferranti, dated December 3, 1907. Fig. 1 in this patent shows the combustion and mixing chamber 21 described above, and Fig. 4 shows two such combustion and mixing chambers C, C supplying highly superheated steam to a turbine S directly connected to a generator t.

The wall 119 completely surrounds the central portion of room 45, thus forming a gas cooling chamber. This cooling chamber is divided into two sealed compartments by the wall 111, the evaporating boiler 113 and the wall 112. Wall 112 extends downwardly through the water which fills these two compartments all the way to the bottom thereof, so that there is no communication between the two compartments in the exhaust side of evaporating boiler 113. The wall 111, Fig. 2, extends into the water filling the bottoms of the intake compartments, as, for instance, compartments 101 and 106, to points short of the bottoms thereof, so that water from compartment 106 can flow under wall 111 to compartment 101 or vice versa, even though the water surfaces in these two compartments are subject to different surface pressures and in consequence have different surface elevations. Water from compartments 101, 102, 103, 104, 105 and 106, 107, 108, 109 and 110 is sprayed into the gases above them so as to cool these gases. By way of illustration, a spray system for this purpose is shown for the compartments 109 and 104 (see Fig. 2 and Fig. 3). Similar spray systems (not shown) are provided for compartments 110-105, 108-103, 106-101, 107 and 102. Water is drawn from the bottoms of the compartments by pump 133 and is delivered by the pump to the top of compartments 109-104 by pipe 132 which branches out into many spray heads 134 (Fig. 2 and Fig. 3), from which emitted spray deluges the gases in the tops of said compartments. Clean cold water is pumped into compartments 105 and 110, by suitable means (not shown), and flows over the weir boards 118 and 124 into compartments 104 and 109. The cold water rapidly heats up in compartments 105 and 110 so as to flow over into compartments 104, 109 raised 20° F. to 40° F. in temperature. The

gases passing through compartments 104, 105 and 109, 110 are rapidly cooled and pass from compartment 110 through fan intake ducts 140 to fan 135 (Fig. 3 and Fig. 5), being discharged through duct 137 into stack 46. From compartment 105 the gases therein pass through compressor suction pipe 139 through axial compressor 138 into pipe 137 and thence to stack 46.

The hot exhaust gases from flues 51 and 15 pass down around the heat reclaiming tube sets 125 (see Fig. 4) and thence out into chambers 106 and 101 as shown by arrows a and b (see Fig. 2). These gases pass through baffles 131 and 131, which preferably comprise horizontal louvres, adapted to keep the spray in chambers 106, 101 from splashing on to the tubes 125. Now it is well known that as water spray passes through hot gases, the gases are rapidly cooled and approach the dew point, while the water spray is rapidly raised in temperature to approach the dew point. The sensible heat in the gases above the dew point is used up in evaporating water. As the saturated gases then pass on to cooler and cooler spray, the water vapor initially in these gases as steam, as well as that evaporated as in chambers 101 and 106, condenses and gives up its heat to the water until the gases discharge up stack 46 at a temperature of about 120° F. The discharged gases generally will contain less than ten per cent water vapor (by weight). Gases entering from the exhaust flue 15 vary in the order of over fifty per cent water vapor by weight. However very little water is taken from the gases received from flue 51, but much heat is salvaged as well as condensate obtained, since the sensible heat in these gases goes first into latent heat in vapor and then into sensible heat in the water spray.

Cold water is pumped into compartments 105 and 110 and takes the levels L and L' respectively as shown in Fig. 3, wherein wall 112 is cut away to show the level in compartment 110. The water flows ultimately into compartment 106 dropping in level only slightly on its way. The level L in compartments 105, and corresponding levels in 104, 103, 102 and 101 are higher than the level L' in compartment 110, and corresponding levels in 109, 108, 107 and 106 since the first group of compartments are under a vacuum produced by the powerful axial air compressor 138 (Fig. 5), while the second group of compartments are only under a vacuum generally less than one foot of water due to induced draft fan 135 driven by motor 136.

Pump 141-142, driven by motor 143 (Fig. 3), drives hot water from compartments 101 and 106 through header 127 into pipe 125 and through pipe 128 to chamber 148 wherein reduced pressure allows the hot water to give off steam which fills said chamber. The steam pressure in chamber 148 is maintained at 50 P. S. I. by a pressure regulator (not shown) suitably located in pipe 60, so as to maintain the water level in this chamber at the level 149. The still hot water, after having left some of its heat in the steam formed in chamber 148, passes into riser 150. In this riser, as the water rises vertically and falls in pressure, steam is formed and its evaporation cools the rising water. The steam bubbles in the water column 150, lightens this column and circulation is rapid into chamber 160, wherein the water level is maintained at about the level 161, or about 33 lbs. absolute by a pressure regulator (not shown) suitably located in pipe 61. Rate of circulation is retarded as needed by operating butterfly valve 183 by cord 185, arranged to pass

around pulley 184. A weight 186 keeps cord 185 taut. A large part of the water, after giving up heat in chamber 148 at about 50 P. S. I., and in chamber 160 at about 33 P. S. I., returns through pipe 180 and flows down through the lower half of pipe 125 (see Fig. 4), where it receives heat from the hot exhaust turbine gas from flue duct 15.

Part of the water leaving chamber 160 flows up riser 162. Steam bubbles form in this water and hurry its circulation. These steam bubbles separate out in chamber 163 at 22 P. S. I., and the pressure is maintained at 22 P. S. I. by a pressure regulator (not shown) suitably located in pipe 62 and at level 164. The still hot water leaves chamber 163 by way of riser 165 wherein steam bubbles form again and aid in the circulation. This water from riser 165 is received and spreads out slowly through chamber 166, where steam again separates out therefrom at 14 P. S. I., which pressure is maintained by a pressure regulator (not shown) suitably located in pipe 63 at level 167. The hot water entering riser 168 is joined by a larger stream of hot water entering by way of pipe 147. The rate of flow of water through pipe 147 is controlled by turbine wheel 144 driven by variable speed motor 146 through shaft 145. A relatively very great volume of water passes up riser 168 and forms steam bubbles; the steam in chamber 169 being at a pressure of about 6 P. S. I. absolute. The pressure is controlled by pressure regulator (not shown) suitably located in pipes 64, 64 to control water level 176. A large part of the water which has now cooled down to about 170° F. leaves by pipe 114, is returned to chamber 104, passes quickly through chambers 103, 102, 101 and is reheated to about 200° F. and reenters pipe 127 for another cycle. Some water passes up to the 3 P. S. I. chamber 172 and gives up steam at 3 P. S. I. absolute to the condenser 181 (Figs. 3 and 5). Coolant water circulates from power condenser 182 to distilled water condenser 181 and the coolant water from condenser 182 condenses steam in condenser 181. The water leaves evaporating chamber 172 by pipe 120 and is suitably discharged as waste. The temperature of water leaving by pipe 120 is about 140° F. This water when it entered the pipe 128 to rise into chamber 148 had its temperature controlled to about 300° F. so that it gave up about 160 B. t. u. per pound in passing through the evaporators in the form of steam. About 25 B. t. u. per pound is available for useful work when delivered to a turbine or other steam operated mechanism. It is to be understood that the heat reclaiming device accomplishes other useful functions.

1. It reclaims otherwise wasted heat.
2. It produces distilled water.
3. It purges fly ash and acids from the gases.

4. It cools the gases so a smaller fan may exhaust them using less horsepower, and a smaller, lower, and thereafter cheaper stack can be used.

Fig. 5 shows how the steam from evaporator 113 is used as a power fluid to drive turbines 187 and 188 and double flow condensing turbine 189.

Steam from chamber 148 is carried by pipe 60 to enter turbine 188. Additional steam from compartments 160, 163 and 166 is delivered by pipes 61, 62 and 63 to turbine 187 (Figs. 3 and 5) at pressures of about 33 P. S. I., 22 P. S. I. and 14 P. S. I. respectively.

Low pressure steam enters the bottom of turbine 189 to work through the double flow vacuum stages thereof in consort with steam from turbine 187, which enters at the top of turbine 189. Turbines 188, 187 and 189 all connect to axial blower 138. Since the steam in turbine 188 is contami-

nated with burned out air and oil, it is exhausted through pipe 191 into flue 15 to have its heat reclaimed.

As many changes could be made in the above constructions, and many widely different embodiments of this invention could be made without departing from the scope thereof. It is intended that all matter contained in the above description or shown in the accompanying drawings shall be interpreted as illustrative and not in a limiting sense.

What is claimed is:

1. In a power reclaiming system, means to direct flow of a stream of highly heated waste gases containing heat desired to be reclaimed, means to direct flow of a stream of water in counterflow relation to said stream of gases, said latter means including spraying means adapted to promote transfer of heat from the gases to the water in a low temperature range of heat transfer, heat transfer means extending to great depth underground adapted to receive the water stream and to carry the same at high head in juxtaposition to said gases in the high temperature range of heat transfer, whereby all the transferred heat received by the water is carried thereby as sensible heat, and heat reclaiming means through which the water from said heat transfer means is caused to rise, said reclaiming means being adapted to progressively extract the heat from the rising water in the form of steam and subject to use at a temperature very little below the extraction temperature in the waste gas stream.

2. In a power heat reclaiming system, means to direct flow of a stream of highly heated waste gases containing heat desired to be reclaimed, means to direct flow of a stream of water in counterflow relation to said stream of gases whereby heat from the gases is transferred to the water, a plurality of vertically disposed and successively communicating evaporator chambers through which the heated water stream is caused to rise in successive stages of diminishing pressure and temperature and release its heat in the form of steam for power application, and means to return at least part of the cooled water stream for recirculation in heat transfer relation to the stream of hot gases.

3. In a power heat reclaiming system, means to direct flow of a stream of highly heated waste gases containing heat desired to be reclaimed, a system of pipes bathed by said stream of gases, said pipes being adapted to circulate water in counterflow relation to said stream of gases subject to transfer thereto of heat from said gases, said pipes extending underground to relatively great depth whereby the water is subjected to hydrostatic pressure exceeding the vapor pressure thereof, and a plurality of vertically disposed and successively communicating evaporating chambers through which heated water from the pipe system is caused to rise and release its heat in the form of steam for power application.

4. In a power heat reclaiming system, water supply means substantially at ground surface, a water conduit system to receive water from said supply means, said water conduit system extending underground to great depth, means to supply waste heat for transfer to water descending said conduit system, and a succession of evaporating chambers extending from the low point of said conduit system upwardly to ground surface through which heated water ascends upon discharge from said conduit system for return to said water supply means, whereby the water as-

cending through said evaporator chambers releases its heat in the form of steam for power application.

5. In a power heat reclaiming system, water supply means substantially at ground surface, a water conduit system to receive water from said supply means, said water conduit system extending underground to great depth, means to supply waste heat for transfer to water descending said conduit system, a succession of evaporating chambers extending from the low point of said conduit system upwardly to ground surface through which heated water ascends upon discharge from said conduit system for return to said water supply means, whereby the water ascending through said evaporator chambers releases its heat in the form of steam for power application, and means to maintain pressure in each said evaporating

chamber at substantially a predetermined value.

6. In a power heat reclaiming system, means for circulating water from substantially ground level to great depth underground and back to ground level, means to transfer heat from a hot waste power exhaust fluid to the descending water, means to control the temperature of the descending water whereby its vapor pressure throughout its descending path may not exceed its hydrostatic pressure while passing from a low pressure condition at the top to a high pressure condition at the bottom, and means to pass the ascending hot water under conditions whereby it releases its heat in the form of steam, subject for use as power developing energy while at the same time promoting circulation of the water in the circuit thereof.

FRAZER W. GAY.
